UNITED STATES PATENT OFFICE.

WILLIAM F. PETTES AND ARTHUR E. SPICER, OF NEW YORK, N. Y., ASSIGNEES TO SAID PETTES.

MEANS FOR AUTOMATICALLY STOPPING RAILROAD-MOTORS.

Specification of Letters Patent.

Patented Feb. 23, 1915.

1,129,425.

Application filed March 28, 1913. Serial No. 757,374.

To all whom it may concern:

Be it known that we, WILLIAM F. PETTES and ARTHUR E. SPICER, citizens of the United States, and residents of the borough 5 of Brooklyn, county of Kings, and city and State of New York, have invented certain new and useful Improvements in Means for Automatically Stopping Railroad-Motors, of which the following is a specification.

10 The object of our invention is the provision of adequate and practical means whereby track motors may be positively and automatically stopped if the track in advance is not clear and safe, so that should 15 an engineer inadvertently or intentionally disregard caution or danger signals no harm can result.

Our invention consists primarily in electrically actuated means whereby the source 20 of power to the motor is automatically shut off and the air brake applied unless the track signal is favorably set to indicate a clear track and right of way, as hereinafter more fully described and claimed specifically; and 25 secondarily the invention includes certain incidental features in the relative arrangement and construction of parts and appliances.

In the accompanying drawing, Figure 1, 30 is a diagrammatic representation, necessarily more or less symbolical, of our system as applied to a steam locomotive or other form of motor using fluid pressure as a source of power; Fig. 2, a similar view showing our system as adapted to the use of electricity as a motive or controlling power; Fig. 3, a 35 similar view showing a modification thereof; Fig. 4, a diagrammatic detail of the triple contact circuit switch.

40 A represents a semaphore post, and a, a semaphore signaling device of usual and well known construction, and operation. Attached to the vertical signal rod a', is a bracket arm a", having a vertical member a", on which is mounted a flexible wiping contact a", Fig. 4. This wiping contact a", obviously travels up and down with the semaphore rod a', as the latter is operated to set the signal. Situated in the line of travel of the 45 wiping contact a", are three contact plates 1, 2 and 3, preferably although not necessarily, arranged in a cylindrical support such as A', the construction of which is illustrated more particularly in Fig. 4.

50 55 b', represents an inclosing cylindrical cas-

ing in which the contact plates (rings in this instance) 1, 2, 3, are mounted, the same being insulated (b") from the casing b', if the latter is metallic.

The annular contact plate 1, is provided 60 with metallic spring wipers or contacts a", a", which insure the electric connection with the metallic member a", regardless of the position of the latter, thereby keeping the wiper a", through the wire b", in constant 65 electrical connection with the battery B, which battery is also connected by wire b", with one rail t, of the track T.

The annular contact plate 2, communicates 70 through wire b", with the primary or caution-signal third rail t", and through the wire b", with the usual electrical testing means Z, which latter also communicates through wire t", with said cautionary third rail t". This preliminary or cautionary 75 third rail t", is of course situated a considerable distance in advance of the semaphore A, to contact with a brush on the motor in time to warn the driver to slow down.

The third annular contact plate 3, is connected by wire b", with the positive-stop 80 third rail t", and through the wire b", with the electrical testing means Z, which latter is in turn connected with the said positive stop third rail t", by the wire b".

85 The rails t, t', of the track T, are electrically connected, as at t", and the rail t', is connected with the testing means Z, by the wire b",—a battery B', being interposed in said connection b", to operate the signal 90 tower or station apparatus, which may include plug sockets p, p', by means of which signals may be set if the semaphore mechanism is out of order.

95 One wheel w, of the motor is in electrical connection with the rail t', and said motor carries a contact brush c, positioned to engage with the auxiliary third rail t", so that if the signal is set at caution with the wiper 100 a", in engagement with the annular contact plate 2, thereby including said auxiliary third rail in the electrical circuit, when the said brush c, contacts with said auxiliary third rail t", one or more signals (as the bell c", or light c", or both) will be actuated on 105 the motor through the medium of the wires c", c", thereby cautioning the motor driver to slow down and proceed carefully.

110 When the block signal is fully set with the wiper a", in contact with the plate 3, thereby

- putting the positive stop third rail t^4 , in electrical circuit, and presuming the motor to be a locomotive using steam as the motive power, as illustrated in the diagram Fig. 1, if the contact brush c' , on the locomotive encounters the positive-stop third rail t^4 , the current will flow through wire d' , to and through the electromagnets D, returning to the rail t' , through the wire d^2 . As a result the armature d , will be drawn toward the electromagnet D, with sufficient force to withdraw the detent or trip d^3 , which is attached to the armature d , away from the shoulder e , on the plunger rod e' , against the resistance of the spring e^2 , thereby allowing the spring e^2 , to project the plunger rod e' , forward. The spring e^2 , is interposed between a shoulder on the plunger rod e' , and the rear of the cylinder e^3 , and the forward end of the plunger rod e' , controls a slide valve e^4 , in the valve chamber e^5 , interposed in the main steam supply e^6 , between the boiler and the engineer's valve. Thus the forward thrust of the plunger rod e' , when released by the detent d^3 , shuts off the supply of steam to the engine through the main steam supply e^6 , at the same time bringing the port e^{14} , in the slide valve e^4 , into coincidence with the pipe f , thereby admitting the passage of steam therethrough to cylinder H, to operate the air brake mechanism J. During this forward thrust of the plunger rod e' , an inclined surface thereon e^{11} , forces inward the plunger i , against the resistance of a spring i' , (Fig. 1) thereby making record of the time on a clock sheet i^2 , in the time clock i^3 , indicated symbolically in the drawings. As soon as the inclined wedge surface e^{11} , clears the indicator plunger i , the latter springs into engagement with a shoulder e^x , in the plunger rod e' , and thereby locks the latter against retraction until released by means not available or accessible to the engineer. For this reason the time clock i^3 , actuating cam e^{11} , and locking shoulder e^x , are preferably incased in a sealed compartment, so that the engine cannot be again started until released by say, the conductor of the train, the signal tower operator, or some one of competent authority having a releasing key or device.
- In order to cut out the electric current after the forward stroke of the plunger rod e' , has cut off the power and recorded the act in the time clock i^3 , as hereinbefore set forth, the plunger c' , is formed with a circuit breaker e^7 , which contacts with the switch d^{22} , interposed in the connection d^2 .
- The cylinder H, contains a piston h , the rod h' , of which carries a rack gear h^2 , engaging with the gear j , controlling the air valve for operating the usual air-brake mechanism represented symbolically in the drawings. During this operation the air in

front of the piston h , acts as a cushion to retard the action of the piston and apply the air gradually, and to regulate this action the cylinder H, is provided with an outlet or escape cock h'' , and said cylinder may also be provided with relief valves h^{22} , and h^8 , to facilitate the retraction of the piston to its normal position at the forward end of the cylinder adjacent to the steam pipe f .

When electricity is the motive power used, or when electricity is used to "spark" a hydro-carbon motor, the plunger rod e' , when released as hereinbefore described breaks the operating circuit by opening a switch therein, as the switch k , interposed in said operative circuit of which the conductors k' , k^2 , in Fig. 2, form a part. In this arrangement when the brush c' , contacts with the positive-stop third rail t^4 , the current not only passes through the electromagnets D, to release the plunger rod e' , but it also passes through the conductor d^{11} , to a small electric motor M, which through a series of gears m , m' , m^2 , operates the air valve gear j , controlling the brake mechanism J, the air in the cylinder H, retarding the action thereof through the medium of the piston h , and rack gear h^2 , as before set forth. In this case an arm h^{23} , on the rack h^2 , contacts with a switch m^3 , to open the circuit.

In the arrangement shown in Fig. 3, the battery B, is omitted, and a generator (shown symbolically) on the locomotive is substituted, but otherwise the cycle of operations hereinbefore set forth is essentially the same,—the cautionary signals being set by the contact of the locomotive brush c , with the primary third rail t^3 , and the motive power being positively shut off and locked by the contact of the locomotive brush c' , with the secondary or positive stop third rail t^4 . The lighting power of a train may be used as a substitute for the generator G, in some cases, with like effect.

The trip d^3 , may be operated manually on the locomotive in case of emergency by means of a handle or retracting device r . In any case the release of the plunger e' , shuts off the motive power and automatically locks the parts so that the motor cannot be started again until formally released by special means in the possession of a person other than the engineer or operator of the locomotive, using the latter term in its broader sense as covering motors generally.

In unlocking the plunger e' , by the depression of the spring bolt i , of the time recording clock mechanism i^3 , the time of release is recorded automatically, thus affording an accurate record of the time between the cutting off of the motive power and the release thereof.

w' , is a contact switch in the power or signal station, interposed in the tripping

circuit, and which has to be opened before the motor can proceed. In other words, when the switch w' , is closed the current flows from the battery B' , b^{10} and t^2 through the track rails t , t' , the positive stop third rail t^4 , and brush c' , to tripping and brake mechanism before described, and the motor cannot proceed.

In case the semaphore is inoperative like results may be attained by the use of the plug sockets p , p' . Thus the effect of plugging p , would be to complete the tripping circuit the same as if contact were made between brush a^4 , and contact plate 3; and the effect of plugging p' , would be to complete the cautionary circuit the same as if the brush a^4 , contacted with the plate 2. When the brush a^4 , is in engagement with contact plate 1, only, there is no electrical connection between the third rails t^3 , and t^4 , and the main track T, and hence the tripping circuit is out of commission and the motor can proceed.

It is to be understood that the power is inevitably cut off before the brakes are applied; and that the latter are applied gradually so as to prevent shock and jar.

By the term track motor as used herein we mean to designate locomotives, electric motors, or any other power driven motor traveling on tracks.

What we claim as our invention and desire to secure by Letters Patent is,

1. Means for automatically signaling and stopping track motors, comprising a plural contact switch, a semaphore, said switch being actuated by said semaphore, a caution-signal circuit connected with one of said contacts and comprising an auxiliary rail, a brush on the motor adapted to contact therewith and close the circuit, electric signals on the motor interposed in said caution-signal circuit, together with a positive-stop circuit connected with another of said contacts of the switch and comprising a positive-stop third rail, a brush on the

motor adapted to contact with said positive-stop third rail and close the said positive-stop circuit, an electro-magnet interposed in the latter circuit, a trip actuated thereby, a motive power throttle, air brake mechanism, means controlled by said trip for operating the same and for automatically opening said positive-stop circuit, a reciprocating member with a cam surface, an indicator plunger co-operating with said member and a spring-actuated member engageable with said cam surface, and a device for automatically locking said trip-controlled means in its released position.

2. Means for automatically signaling and stopping track motors, comprising a plural contact switch, a semaphore, said switch being actuated by said semaphore, a caution-signal circuit connected with one of said contacts and comprising an auxiliary rail, a brush on the motor adapted to contact therewith and close the circuit, electric signals on the motor interposed in said caution-signal circuit, together with a positive-stop circuit connected with another of said contacts of the switch and comprising a positive-stop third rail, a brush on the motor adapted to contact with said positive-stop third rail and close the said positive-stop circuit, an electro-magnet interposed in the latter circuit, a trip actuated thereby, a motive power throttle, air brake mechanism, means controlled by said trip for operating the same and for automatically opening said positive-stop circuit, a device for automatically locking said trip-controlled means in its released position, a reciprocating member having a cam surface, an indicator plunger co-operating with said means, and a spring-actuated bolt engageable with said cam surface.
